GUIDE FOR THE ENGAGEMENT OF STUD CARRYING COLLARS ON A GROOVED SHAFT

Charles Labrie, 278 Cousineau St., Pont Vieux,
Quebec, Canada

Filed Apr. 22, 1960, Ser. No. 24,059

6 Claims. (Cl. 242—68.1)

The present invention relates to guiding means for facilitating the insertion of stud carrying collars on a longitudinally grooved shaft.

For winding tape, such as adhesive tape and the like, on cardboard rings, a winder is used which comprises essentially a rotary shaft provided with a longitudinal groove. The cardboard rings are inserted on said shaft with the interposition of metal spacer rings or collars provided with an inwardly directed stud engaging the groove whereby said spacer rings serve to drive the cardboard rings for winding the tape thereon. When adhesive tape is wound, two winder shafts are used and the sheet of adhesive is first cut and the strips are alternatively wound on the cardboard rings of the two shafts in order to prevent sticking of the edges of the adjacent strips.

When the winding is completed, a tightening screw is unscrewed from one end of the shaft and the spacer collars and reels of tape are removed from the shaft and the collars and new cardboard rings are reinserted on the shaft. However, each collar has to be rotated by hand to bring its stud into alignment with the longitudinal groove of the shaft in order to insert the collar on the shaft. This is a time consuming operation.

The main object of the present invention resides therefore in the provision of guiding means which will automatically align the studs of the collars with the longitudinal groove of the shaft and will therefore considerably facilitate and accelerate stringing of the collars and cardboard rings for the winding operation.

Another important object of the present invention resides in the provision of a guide of the character described which form an integral part of the winding shaft.

Still another object of the present invention resides in the provision of a guide of the character described which is removably adapted at one end of the grooved shaft.

Still another important object of the present invention resides in the provision of guiding means of the character described which positively prevent blocking or jamming of the stud carrying collars on the shaft during stringing.

The foregoing and other important objects of the present invention will become more apparent during the following disclosure and by referring to the drawings, in which:

Figure 1 is a front elevational view of a grooved shaft provided with the guiding means of the invention;

Figure 2 is a side elevation of the same shaft;

Figure 3 is a longitudinal section along line 3—3 of Figure 1;

Figure 4 is a back elevation of the same shaft;

Figure 5 is an elevation of the complete shaft provided with the guiding means of the invention and showing an assembly of stud carrying collars and cardboard rings thereon;

Figure 6 is an end view of the shaft of Figure 1;

Figure 7 is a cross-section along line 7—7 of Figure 2; and

2

Figure 8 is a front elevation of a guide in accordance with the invention removably connected to a grooved shaft, partly broken away to show the threaded connection.

5 In the description and the accompanying drawings, the same reference characters indicate the same elements throughout.

Reference numeral 1 indicates a shaft provided with a longitudinally extending groove 2 having a bottom and longitudinal sides 20 and 21. As previously explained, it is desired to string in a rapid and easy manner the spacer collars 3 made of metal and provided with an internally directed tooth or stud 4, such that the stud will engage the groove 2, for rotation of collar 3 by shaft 1. The outer end portion 5 of shaft 1 is of the same diameter as the bottom of groove 2. The sides 20 and 21 of groove 2 flare at the end of groove 2 adjacent end 5 of shaft 1 to define inclined side portions 22 and 23 which extend spirally around the shaft to join at an apex 6 (see Figure 4) which lies on the line diametrically opposed to the longitudinal side 20 of groove 2.

A raised lozenge shaped boss 7 is formed on the portion 5 of the shaft. The outer face of said lozenge is cylindrical and has the same diameter as shaft 1; said lozenge is elongated with its two opposed outer and inner apices 24 and 25 respectively disposed along a longitudinal line aligned with the longitudinal side 20 of groove 2. Thus, the two inner inclined sides 26 and 27 of the lozenge 7 are disposed adjacent but spaced from inclined sides 22 and 23 of the groove such as to define therewith a bifurcation of groove 2 into two oppositely directed and inclined branches opening into a flaring portion defined by the outer portions of sides 22 and 23 and the outer inclined sides 28 and 29 of lozenge 7. The outer apex 24 of lozenge 7 is diametrically opposed and transversely aligned with apex 6.

Due to the eccentric position of lozenge 7 with respect to groove 2, groove side 20 starts to flare out at a point further removed from the inner apex 25 of lozenge 7 than the starting point of flaring of side 21.

As shown in Figure 5, the shaft 1 is provided at its end opposite end 5 with a gear wheel 8 and with abutting nut 9, screwed on the shaft.

In the use of the invention, the shaft 1 is held vertically and cardboard rings 10 are strung alternatively with stud carrying metal collars 3. The stringing is effected at the end 5 of shaft 1. Upon stringing of the collars 3, their stud 4 will pass between the apex 24 of the lozenge 7 and the apex 6 defined by sides 22 and 23; from then on, the stud will be guided by sides 22 and 23 until the stud engages the straight part of groove 2.

The lozenge 7 is necessary because it maintains the full diameter of shaft 1 up to apices 6 and 24, and thus prevent the collars 3 from becoming inclined and wedging on the shaft, in the case where the stud 4 would abut against apex 6.

Once all the collars 3 and cardboard rings 10 have been strung on the shaft, they are tightened one against the other by means of nut 11 engaging threads (not shown) made on the portion 5 of the shaft, outside of and adjacent lozenge 7. The shaft and assembled collars and rings may then be placed in driving position in the winder.

The eccentric position of the inner apex 25 of lozenge 7 prevents the stud 4 from butting against said apex when the collars 3 are unstrung after the winding of the tape on cardboard rings 10.

70 In the modified form of the invention in accordance with the present invention and shown in Figure 8, the guide of the invention is constituted by a separate part,

In this case, the shaft 12 has a threaded nipple 13 engaging with a threaded socket made in the guide 14 which forms a removable prolongation or extension of shaft 12. The part 14 has a groove 15 which is aligned with the groove of shaft 12 (not shown) and which corresponds to groove 2 of shaft 1. The guide 14 has flaring sides for groove 15 and a lozenge 17 corresponding to lozenge 7 of the first embodiment. The outer end of the guide 14 is tapered, as shown at 16, to facilitate stringing of the collars and ring. Threads (not shown) corresponding to threads 11' of the first embodiment are made on shaft 12 adjacent nipple 13.

While preferred embodiments in accordance with the present invention have been illustrated and described, it is understood that various modifications may be resorted to without departing from the spirit and scope of the appended claims.

What I claim is:

1. A guide for stringing stud carrying collars on a longitudinally grooved shaft, comprising a shaft section having a longitudinal groove with a bottom and longitudinal sides, said sides flaring at one end of said groove to form inclined side portions joining into a first apex at a point of the shaft diametrically opposed to said groove, the bottom of said groove defining a surface which extends between said inclined side portions, and a lozenge shaped boss on said surface disposed between said inclined side portions and defining with said inclined side portions and two of its own sides, a bifurcation of

10 said groove, said lozenge shaped boss having an outer and an inner apex disposed along a line parallel to said longitudinal groove.

5 2. A guide as claimed in claim 1, wherein said lozenge shaped boss has its apices laterally offset from the center of said groove.

3. A guide as claimed in claim 1, wherein the inclined side portions meet said longitudinal sides of said groove at points unequally spaced from the adjacent inner apex of said lozenge shaped boss.

15 4. A guide as claimed in claim 3, wherein the apices of said lozenge shaped boss are aligned with the one longitudinal side of said groove the meeting point, of which, with the associated inclined side portion is the more distant from the adjacent inner apex of said lozenge shaped boss.

5. A guide as claimed in claim 1, wherein the outer apex of said lozenge shaped boss is disposed in substantially transverse alignment with said first apex.

6. A guide as claimed in claim 1, wherein the external surface of said lozenge shaped boss is curved on a diameter equal to the diameter of said shaft section.
